UNITED STATES PATENT OFFICE

148,524

DESIGN FOR A STYLUS POINT SUPPORT FOR PHONOGRAPHS

John M. Dean, Putnam, Conn., assignor to The
General Phonograph Manufacturing Company,
Putnam, Conn., a corporation of New York

Application August 21, 1946, Serial No. 132,678

Term of patent 14 years

(Cl. D26—14)

To all whom it may concern:

Be it known that I, John M. Dean, a citizen of the United States, residing at Putnam, in the county of Windham and State of Connecticut, have invented a new, original, and ornamental Design for Stylus Point Support for Phonographs, of which the following is a specification, reference being had to the accompanying drawing, forming a part hereof, in which:

Fig. 1 is a side elevational view of the stylus point support for phonographs showing my new design;

Fig. 2 is a top plan view thereof;

Fig. 3 is an end elevational view; and

Fig. 4 is a bottom plan view.

The characteristic features of my design reside

in the portions shown by means of full lines in the drawing.

I claim:

The ornamental design for a stylus point support for phonographs, substantially as shown and described.

JOHN M. DEAN.
